JAMES G. BLUNT, OF SCHENECTADY, NEW YORK

LOCOMOTIVE BOILER SUPPORT

Application filed September 29, 1930. Serial No. 485,119.

This invention relates to boiler supports and more particularly to a support for use on a locomotive of the two stage or double pressure boiler type. Locomotives of this class 5 embody a forward low pressure boiler section containing fire tubes and a rear high pressure boiler section forming what is commonly termed a fire box and combustion chamber containing water tubes, connected therewith, 10 the two sections being detachable. Where the words fire box or high pressure boiler section are used herein they will be understood to mean the entire rear boiler section of the locomotive including the fire box proper and 15 the combustion chamber for such locomotives as have both a fire box and a combustion chamber and to refer to the fire box section alone for such locomotives as do not include a separate combustion chamber.

20 An object of the present invention is to provide a boiler supporting structure which will furnish an improved means of support and will permit a relative longitudinal movement between the boiler and the frame of the locomotive to compensate for the expansion and 25 contraction of the boiler. Other objects are to provide a support such as the aforesaid which will include means of support for the fire box and means of attachment between the forward low pressure boiler section and the fire box supporting structure. A further object of the invention is to provide a boiler support of the aforescribed character which 30 will also embody means for supporting various locomotive accessories.

35 In the accompanying drawings: Figure 1 is a side elevation of a part of a locomotive with the invention applied thereto; Fig. 2 is a vertical section on the line II—II of Fig. 1; Fig. 3 is a side view of the supporting saddle; Fig. 4 is a plan view of a part of the structure shown in Fig. 3; Fig. 5 is a rear view of a part of the structure shown in Fig. 3; Fig. 6 is a section on the line IV—IV of Fig. 3; and, Fig. 7 is a fragmentary sectional view of the structure shown in Fig. 1, taken on the line VII—VII of Fig. 1.

40 In the practice of the invention referring descriptively to the specific embodiment thereof which is herein exemplified as ap-

plied to a locomotive having a frame 1, of the usual type and construction, the forward low pressure section 2 of the boiler containing fire tubes (not shown) and the rear high-pressure section 3 which comprises the fire box and 55 combustion chamber and contains water tubes (not shown) are detachably connected together.

5 A double supporting saddle 4 is disposed between the low-pressure section 2 of the boiler and the frame 1 of the locomotive. The saddle comprises an integral casting (Figs. 3 to 6) having U-shaped sections 5, disposed transversely beneath the boiler with flanges 6 formed on their upper sides shaped 60 to correspond with the curvature of the boiler shell. The sections 5 are open on their upper sides between the flanges 6 which embrace the lower portion of the boiler shell. Holes 7 are formed in the flanges for the reception of 65 suitable studs or rivets by which the saddles are connected to the boiler. The sections 5 are connected with each other by tubular sections 8 at their opposite ends.

70 For the purpose of drawing the saddle 75 firmly against the boiler, and of providing additional support for the accessories support bracket, hereinafter described, brace rods 9 are provided opposite the ends of each of the flanges 6. Brace lugs 10 are riveted to the 80 boiler shell and the upper ends of the brace rods are pivotally connected thereto by bolts 11. The lower ends of the brace rods pass through holes formed in the saddle connecting sections 8 and are threaded and secured 85 in place by nuts, by adjustment of which the saddle may be drawn as firmly as desired against the boiler.

90 On each of the opposite outer sides of the saddle a lug 12 is formed, extending downward from the base of the same. A sliding expansion shoe 13 is bolted to the lug 12. Secured to the engine frame 1 is a cross-tie 14.

95 The shoe 13 bears upon the cross-tie and is supported thereby, the shoe being provided with a liner of suitable metal such as brass or bronze to permit free longitudinal sliding movement thereon when the boiler expands or contracts under its varying temperature. Arms 25 formed on the cross-tie provide a 100

dove-tail socket for the shoe 13 and serve to prevent relative vertical or lateral movement of the same.

The opposite ends of the rear transverse section 5 are formed with outwardly and rearwardly extending tubular arms 15 having flanges 16 formed on their ends. Supporting beams 17 extend rearwardly from the flanges 16, and are provided at their forward ends with corresponding flanges 18, to which the flanges 16 are bolted. The beams 17 are step-shaped in cross section and the lower ends of inner sheets 26 of the side casing, of the fire box section of the locomotive, are riveted to the respective adjacent inner sides of the said beams and are thereby supported. The lower ends of outer sheets 27 of the side casing are secured to the respective adjacent outer sides of beams 17, by eye bolts 28 which pass through the beams and the sheets with their eyes projecting on the outside of said sheets. Supporting beams 19 are longitudinally disposed at the bottom of the fire box section, and are secured by bolts 29, at their forward ends 20, to horizontal flanges 21, formed on the base of the rear transverse section 5, of the saddle. The beams 19 are substantially box-shaped in cross section, as shown in Fig. 7. Upper sheet 30 of the bottom casing of the firebox is supported by the beams 19, spacing rings 31 being disposed between the sheet and the beams, and bolts 32 being passed through the beams, rings and sheet. Central outside sheet 33, of the bottom casing, is riveted at its sides to the respective adjacent lower sides of the beams 19, and outside lower sheets 34 are riveted to brackets 35 at their inner sides, the brackets being in turn welded to the adjacent outer sides of the beams 19. The upper ends of the sheets 34 are welded to brackets 36, and bolts 37 are passed through the brackets 36, thereby securing the same and supporting the sheets 34. The upper extremities of the sheets 34 are shaped around the lower portions of the beams 17. By the foregoing construction it will be seen that the saddle is adapted to provide supporting means for the fire box casing and a means of attachment between the same and the low pressure section of the boiler.

Integrally formed on the outer sides of the connecting sections 8 are brackets 22 which comprise upper extensions 23 and lower extensions 24 providing a supporting rack for locomotive accessories such as air pumps, feed water heaters, reverse gears and the like, an air pump being indicated in place in Figs. 1 and 2 by way of illustration.

While a specific embodiment of the invention is herein described, there are many and various changes and modifications in the details of construction of the device which may be found desirable and which will be apparent to those skilled in the art, and it will be

understood that all and any such changes and modifications are contemplated as within the spirit of the invention and the scope of the appended claims.

The invention claimed and desired to be 70 secured by Letters Patent is:

1. A supporting saddle for locomotive boilers comprising a plurality of tubular sections transversely disposed beneath the boiler shaped to correspond with the curvature 75 of the boiler shell and having the portion of their upper sides adjacent the same open and formed with flanges adapted to embrace the said boiler shell, and tubular connecting sections integrally formed at the adjacent ends 80 of said transverse sections.

2. In a locomotive, the combination of a frame; a boiler; and a supporting saddle for said boiler comprising a plurality of transverse sections spaced apart and having flanges 85 formed thereon adapted to engage the shell of the boiler, connecting sections between the supporting sections, and supporting members on said connecting sections bearing on the said frame and adaptable for slidable 90 longitudinal movement relative thereto.

3. In a locomotive, the combination of a frame; a boiler; and a supporting saddle comprising a plurality of tubular sections transversely disposed beneath the boiler, shaped to correspond with the curvature of the boiler shell, and having the portion of their upper sides adjacent the same open and formed with flanges adapted to embrace the said boiler shell for securely joining the tubular sections thereto, tubular sections integrally formed at the adjacent ends of said transverse sections for connecting the same, and supporting members formed on said connecting sections bearing on the said frame 100 and adapted for slidable longitudinal movement relative thereto.

4. A supporting saddle for locomotive boilers, comprising a plurality of transverse sections spaced apart and having flanges 110 formed thereon adapted to engage the shell of the boiler, connecting sections between said supporting sections, supporting members formed on said connecting sections, and a brace member adapted to be secured to the side of a boiler and to one of said connecting sections.

5. A supporting saddle for locomotive boilers, comprising a plurality of transverse sections spaced apart and having flanges 120 formed thereon adapted to engage the shell of the boiler, connecting sections between said supporting sections, supporting members formed on said connecting sections, lugs 125 adapted to be mounted on the sides of a boiler, and brace rods pivotally connected to said lugs at their upper ends and adjustably connected to the said connecting sections at their lower ends and adapted to draw the said 130

saddle firmly against the said boiler shell and to provide additional support.

6. In a locomotive, the combination of a frame; a boiler; a saddle secured to the shell of the boiler to support the same; supporting means on said saddle bearing on said frame and adaptable for slidable longitudinal movement relative thereto; and a brace member secured to the side of the said boiler and attached to said saddle adapted to draw the said saddle firmly against the said boiler shell and to provide additional support.

7. In a locomotive comprising a frame, a forward low pressure boiler section and a rear high pressure boiler section detachably connected to said forward section, a supporting saddle secured to the shell of the forward boiler section, supporting means on the said saddle bearing on said frame, and supporting means for said rear boiler section disposed within the said rear section and connected at their forward ends with said saddle.

8. In a locomotive comprising a frame, a forward low pressure boiler section and a rear high pressure boiler section detachably connected to said forward section, a supporting saddle for said forward section comprising a plurality of transverse sections spaced apart and having flanges formed thereon engaging the shell of the forward boiler section and connecting sections between said transverse sections, the rear connecting section having extensions formed thereon with flange members at their ends facing said rear boiler section, supporting beams for and disposed within the rear boiler section having flanges formed on their forward ends connected with said connecting section flanges, and supporting means on said saddle connecting sections bearing on said frame and adaptable for slidable longitudinal movement relative thereto.

9. In a locomotive comprising a forward low pressure boiler section and a rear high pressure boiler section detachably connected to said forward section, a supporting saddle secured to the shell of the forward boiler section, supporting means for said rear boiler section disposed within the said rear boiler section beneath said fire box, connected to the said saddle and supported thereby, and means disposed on said saddle for supporting the same and the said rear boiler section supporting means.

55 10. In a locomotive, a frame; a forward low pressure boiler section; a rear high pressure boiler section, detachably connected to said forward section; a supporting saddle for the said forward boiler section comprising a plurality of transverse sections spaced apart and having flanges formed thereon engaging the said forward boiler section, and connecting sections between said transverse sections; supporting means for said rear boiler section extending within the said rear

boiler section connected to flanges formed on the rear transverse saddle section and supported thereby; and means disposed on said connecting saddle sections for supporting the said saddle and said rear boiler section supporting means, bearing on the said frame, and adapted for relative longitudinal sliding movement thereon.

11. In a locomotive, a frame; a forward low pressure boiler section; a rear high pressure boiler section, detachably connected to said forward section; a supporting saddle for the said forward boiler section comprising a plurality of transverse sections spaced apart and having flanges formed thereon engaging the said forward boiler section, and connecting sections between said transverse sections, the rear transverse section having flanges formed thereon at its base and the connecting sections having rearward extensions with flanges formed thereon; supporting means extending within said rear boiler section connected at their forward ends to said flanges on the base of the rear transverse section; supporting means within said rear section at the sides thereof, having flanges formed on their forward ends connected with said extension flanges; and supporting means on said connecting saddle sections bearing on the said frame.

12. A supporting saddle for locomotive boilers, comprising a plurality of transverse sections spaced apart and having flanges formed thereon adapted to engage the shell of the boiler, connecting sections between said supporting sections, a bracket member formed on said connecting sections adapted to provide a supporting rack for locomotive accessories, and supporting means formed on said connecting sections.

13. A supporting saddle for locomotive boilers, comprising a plurality of transverse sections spaced apart and having flanges formed thereon adapted to engage the shell of the boiler, connecting sections between the supporting sections, a bracket member formed on one of said connecting sections, adapted to support locomotive accessories, a brace member adapted to be secured to the side of the boiler and attached to the adjacent connecting section, adapted to draw the said saddle firmly against the boiler and to provide additional support for said bracket, and supporting means for said saddle formed on said connecting sections.

14. In a locomotive having a frame and a boiler, a supporting saddle for said boiler comprising a plurality of transverse sections spaced apart and having flanges formed thereon adapted to engage the shell of the boiler, connecting sections between said supporting sections, a bracket member, comprising upper and lower extensions integrally formed on one of said connecting sections adapted to support locomotive accessories,

and supporting members formed on said connecting sections bearing on said frame and adapted for slideable longitudinal movement relative thereto.

15. In a locomotive, the combination of a locomotive frame; a sectional boiler shell, the sections of which being rigidly secured together along their adjacent transverse end margins; a supporting saddle for one of the sections disposed near the transverse line of connection of the two sections; and an extension rigidly carried by the saddle projecting therefrom longitudinally of the boiler abreast of the other shell section and rigidly secured thereto to afford an auxiliary support therefor, said extension being in suspended relationship to the frame of the locomotive.

16. In a locomotive, the combination of a locomotive frame; a sectional boiler shell, the sections of which being rigidly secured together along their adjacent transverse end margins; a supporting saddle for one of the sections disposed near the transverse line of connection of the two sections; and an extension rigidly carried by the saddle projecting therefrom longitudinally of the boiler into and abreast of the other shell section and rigidly secured thereto to afford an auxiliary support therefor, said extension being in suspended relationship to the frame of the locomotive.
